(57) **CLAIM**

The ornamental design for an earthmover tire hydro funnel, as shown and described.

DESCRIPTION

FIG. 1 is a top perspective view of an earthmover tire hydro funnel showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof; and,

FIG. 9 is a top cross-sectional perspective view thereof taken in the direction of line 9-9 of FIG. 4.

The broken lines showing of a rod and clips in FIG. 1-9 are included for the purpose of showing environmental structure and form no part of the claimed design.
